UNITED STATES PATENT OFFICE.

HARRY T. BROOKS AND HAZEN DOUGLAS, OF BALTIMORE, MARYLAND.

BATHER'S WATERPROOF CASE.

Application filed November 6, 1923. Serial No. 673,064.

To all whom it may concern:

Be it known that we, HARRY T. BROOKS and HAZEN DOUGLAS, citizens of the United States, residing at Baltimore city, State of Maryland, have invented certain new and useful Improvements in Bathers' Waterproof Cases, of which the following is a specification.

This invention relates to a receptacle for use by bathers, one of its objects being to provide a simple and compact device of this character that can be carried readily on the belt and which, when closed, will be tightly sealed so as to thoroughly protect its contents from moisture.

Another object is to provide novel means for fastening the closure in shut position, said fastening means also providing an opening device whereby the closure can be forced from sealing position when it is desired to have access to the contents.

With the foregoing and other objects in view which will appear as the description proceeds, the invention consists of certain novel details of construction and combinations of parts which will be hereinafter more fully described and pointed out in the claims it being understood that various changes may be made in the construction and arrangement of the parts without departing from the spirit of the invention as claimed.

In the accompanying drawings the preferred form of the invention has been shown.

35 In said drawings

Figure 1 is an elevation of the device.

Figure 2 is a plan view thereof.

Figure 3 is a vertical longitudinal section.

40 Figure 4 is a section on line 4-4, Figure 1.

Figure 5 is an enlarged section through a portion of the container and cover and showing two positions of the fastener and opener.

45 Referring to the figures by characters of reference 1 designates a container preferably of metal although it can be of any water-proof, non-flexible material. This container has a rigid lining 2 spaced there-

50 from except at its upper end where it is outturned and joined to the wall of the container, as shown at 3. A bead is formed around the upper end of the container for the purpose of reinforcing it, as shown at 4 and a stiffening wire is housed in this bead and is offset therefrom at diametrically op-

posed points to form outstanding loops 4^a and 4^b respectively. Adjacent one of these loops, 4^a, a slot 5 is formed in the wall of the container above the end 3 of the lining, 60 it being understood that said outturned portion 3 of the lining constitutes a seat for a closuré as hereinafter explained.

The container is adapted to be closed and sealed by a cover comprising a plate 6 the bottom face of which is covered by a thick layer of rubber 7 or the like the sides of which are beveled as shown. This cover has a handle in the form of a loop 8 connected thereto whereby it can be handled readily.

An elongated narrow loop 9 of strong spring wire is adapted to extend across the cover and is bent at one end to form an eye 10 pivotally engaging the loop 4^a. From this eye is extended a lifting finger 11 75 adapted normally to project under the margin of the cover, as shown by full lines in Figure 5. The other end of the loop 9 is crooked as at 12 for detachable engagement with the loop 4^b. Nodes 13 are offset from 80 the loop 9 and are adapted to bear against the cover.

Loops 14 are fastened to the container and are designed for engagement by a belt, not shown, whereby the device can be secured to the body of the user. By placing the cover in position and pressing the nodes 13 thereagainst the cover can be forced against its seat and the end 12 of the loop 9 snapped into engagement with loop 4^b. 90 Thus the rubber portion 7 of the cover will be compressed against the seat 3 and the container will be sealed. When it is desired to open the container it is merely necessary to detach the wire loop 9 from the loop 4^b 95 and swing it back, as shown by dotted lines in Figure 5. Thus the finger 11 will engage the margin of the cover plate 6 and pry the cover from its seat.

Obviously a device such as described will 100 constitute a very efficient container for tobacco, matches, and other articles to be used by bathers and which should be kept in a dry state.

What is claimed is:-

1. The combination with a beaded container having a hollow wall with an interior seat, of a closure including an upper rigid plate and a lower resilient tapered disk for engagement with said interior seat, a resilient 110 fastening member, having hinged connection with the bead on the container, hooked at

one end to provide a spring catch and turned downwardly and inwardly at the opposite end to provide a closure prying device.

2. The combination with a beaded container having a hollow wall with an interior seat, of a closure including an upper rigid plate and a lower resilient tapered disk for engagement with said interior seat, a resilient fastening member, having hinged connection with the bead on the container, hooked at one end to provide a spring catch

and turned downwardly and inwardly at the opposite end to provide a closure prying device, said resilient fastening offset having a plurality of downwardly offset portions insuring spring pressure upon the upper rigid disk of the closure. 15

In testimony whereof we have fixed our signatures.

HARRY T. BROOKS.
HAZEN DOUGLAS.
